COMPARTMENTED FOOD CONTAINER OR THE LIKE

John Donald Bostrom, Niles, Ill., assignor to Illinois Tool
Works Inc., Chicago, Ill., a corporation of Delaware

Filed Mar. 15, 1965, Ser. No. 84,258

Term of patent 14 years

(Cl. D58—13)

FIG. 1 is a perspective view of a compartmented food container or the like embodying my new design;

FIG. 2 is a perspective view showing the interior of one of the halves, the other half being substantially identical therewith;

FIG. 3 is a top plan view on enlarged scale showing the outer side of the compartmented food container or the like half shown in FIG. 2;

FIG. 4 is a side elevational view of the container showing the halves thereof slightly separated from each other; and

FIG. 5 is an end view thereof as it appears in closed position, the opposite end being substantially similar thereto.

I claim:

The ornamental design for a compartmented food container or the like, as shown and described.
